CLAIM

The ornamental design for a confectionery piece, as shown and described.

DESCRIPTION

FIG. 1 illustrates a front right perspective view of the confectionery piece showing my new design;

FIG. 2 illustrates a right side elevation view thereof, wherein the left side elevation view is a mirror image of this view;

FIG. 3 illustrates a front elevation view thereof;

FIG. 4 illustrates a rear elevation view thereof;

FIG. 5 illustrates a bottom view thereof; and,

FIG. 6 illustrates a top view thereof.
